DESIGN FOR A COMBINED PAPER WEIGHT, CLOCK, CALENDAR, AND SUPPORT THEREFOR

George W. Blow, New York, N. Y., assignor to
Western Clock Company, Peru, Ill., a corpora-
tion of Illinois

Application August 9, 1935, Serial No. 58,032

Term of patent 7 years

To all whom it may concern:

Be it known that I, George W. Blow, a citizen of the United States, residing in the city of New York, in the county of New York, and State of New York, have invented a new, original, and ornamental Design for a Combined Paper Weight, Clock, Calendar, and Support Therefor, of which the following is a specification, reference being had to the accompanying drawing, forming a part thereof.

In the drawing:

Fig. 1 is a front view of the clock part of the combination.

Fig. 2 is a side view of the clock part of the combination.

Fig. 3 is a front view of the calendar and the support, the printed matter being merely illustrative.

Fig. 4 is a side view of the disclosure in Fig. 3.

Fig. 5 is a side view of the complete combined paper weight, clock and calendar.

The complete design as shown is manufactured and sold as a unit.

I claim:

The ornamental design for a combined paper weight, clock, calendar, and support therefor, as shown and described.

GEORGE W. BLOW.
